Primary Examiner — Cathron C Brooks*Assistant Examiner* — W. A. Teddy Falloway(74) *Attorney, Agent, or Firm* — Thomas | Horstemeyer LLP(57) **CLAIM**

The ornamental design for a plant pot stacker, as shown and described.

DESCRIPTION

FIG. 1 is a perspective view of a plant pot stacker; FIG. 2 is a top view of the plant pot stacker; FIG. 3 is a bottom view of the plant pot stacker; and, FIG. 4 is a side view of the plant pot stacker.

The broken lines illustrate portions of the plant pot stacker that form no part of the claimed design.

1 Claim, 4 Drawing Sheets---
